Primary Examiner — Deanna L Pratt(74) *Attorney, Agent, or Firm* — The Sladkus Law Group(57) **CLAIM**

The ornamental design for a doll stand, as shown and described.

DESCRIPTION

FIG. 1 is a perspective view of a doll stand showing a new design;

FIG. 2 is front view of the doll stand of FIG. 1;

FIG. 3 is a rear view of the doll stand of FIG. 1;

FIG. 4 is a right side view of the doll stand of FIG. 1;

FIG. 5 is a left side view of the doll stand of FIG. 1;

FIG. 6 is a top view of the doll stand of FIG. 1;

FIG. 7 is a bottom view of the doll stand of FIG. 1; and,

FIG. 8 is an exploded view of the doll stand of FIG. 1.

The broken line showing of the doll stand is for the purpose of illustrating portions of the article that form no part of the claimed design.
